UNITED STATES PATENT OFFICE.

ARCHELAUS C. DAKIN, OF CLINTON, MASSACHUSETTS.

GRATE FOR FURNACES.

SPECIFICATION forming part of Letters Patent No. 398,950, dated March 5, 1889.

Application filed September 11, 1888. Serial No. 285,106. (No model.)

To all whom it may concern:

Be it known that I, ARCHELAUS C. DAKIN, of Clinton, in the county of Worcester and State of Massachusetts, have invented certain new and useful Improvements in Grates for Furnaces; and I do hereby declare that the following is a full, clear, and exact description thereof, reference being had to the accompanying drawings and to the letters of reference marked thereon, which form part of this specification, in which—

Figure 1 is a plan view of a grate constructed in accordance with my invention. Fig. 2 is a sectional view of Fig. 1 on line xx . Fig. 3 is a detail sectional view of the same. Fig. 4 is a plan view showing a modified construction of grate. Fig. 5 is a similar view of a second modification.

This invention relates to stoves and furnaces, and its object is to provide improved sectional castings and grates therefor which will permit expansion or contraction of the parts without danger of breakage; and the invention consists in the novel manner of fitting the sections together, and in certain novel details of construction hereinafter described, illustrated in the drawings, and concisely stated in the claims.

Referring to the accompanying drawings by letter, A designates a grate of ordinary form having an annular rim or frame and a series of cross-bars. The frame is formed in two equal sections, B C, as shown, the ends of which may be overlapped and jointed and united by securing-bolts bb . The frame-section B is provided with a series of bars, D D, of varying length, the ends of these bars being preferably reduced, as at d , and adapted to enter sockets or mortises E E, formed at corresponding points in the inner face of section C, so that when united, as described, the bars are properly supported at each end, but can expand or contract by heat without subjecting themselves or the rim-sections to strain.

As shown in Fig. 5, all the bars project from one section and all the mortises are in the opposite section. Preferably, however, I have both bars and sockets provided with

each section, as shown in Figs. 1 and 4. The 50 bars in this instance alternate with the sockets of their respective sections, and the bars of the two sections are so arranged that when the sections are united the bars will be alternately loosely connected to the sections at opposite ends.

Instead of uniting the sections at their ends by bolts b they may be united centrally, as shown in Fig. 4, by means of the central grate-bar, F, which is enlarged and is united 60 at one end to the center of section B, and its other end is lapped in a corresponding recess in the center of section C and secured thereto by a bolt. If desired, both the central and end fastenings may be used in the same 65 grate.

The bars are of such length or so finished at their ends that when the frame-sections are properly united the free ends of the bars will not bind in their respective sockets, so that 70 each bar may contract or expand without disturbing the others.

I have illustrated a circular grate; but the essential idea of the invention is equally applicable to other forms of castings, and, if desired, the frames may be formed in more than two sections, the essential feature of the invention being the properly supporting the bars while allowing each bar to freely and independently expand or contract.

Having described my invention, I claim—

1. A grate composed of two frame-sections connected substantially as described, and a series of grate-bars, each one of which is rigidly connected to or formed with one of the 85 frame-sections at one end and has its free end loosely engaged in a corresponding socket in the opposite frame-section, whereby each bar can expand and contract independently of the other bars, substantially as described.

2. The herein-described grate, composed of the frame-sections B and C, connected at their ends, and each provided with alternate grate-bars and sockets, the ends of the bars of one section being arranged to enter loosely the 95 sockets of the opposite section when the sections are united, substantially as set forth.

3. The combination, in a grate, of the sec-

tion B, formed with alternate grate-bars and sockets, and a central grate-bar, F, with the section C, also formed with alternate grate-bars and sockets and connected at its ends to 5 the ends of section B and centrally to the end of bar F, all constructed and arranged substantially as and for the purpose described.

In testimony that I claim the foregoing as my own I affix my signature in presence of two witnesses.

ARCHELAUS C. DAKIN.
